UNITED STATES PATENT OFFICE.

ALEXANDER T. KASLEY, OF MOORE, PENNSYLVANIA, ASSIGNEE TO WESTINGHOUSE ELECTRIC & MANUFACTURING COMPANY, A CORPORATION OF PENNSYLVANIA.

TURBINE BLADING.

Application filed March 28, 1924. Serial No. 702,489.

To all whom it may concern:

Be it known that I, ALEXANDER T. KASLEY, a citizen of the United States, and a resident of Moore, in the county of Delaware and State of Pennsylvania, have invented a new and useful Improvement in Turbine Blading, of which the following is a specification.

My invention relates to blade fastening means for turbines and it has for its object to provide apparatus of the character designated which may be simply, easily and inexpensively manufactured and installed, and which shall be highly effective in operation to retain turbine blades in place over long periods of service.

In the accompanying drawing, Fig. 1 is a side view in section of a turbine of the single-disc impulse type, being typical of the general type of apparatus in which my invention may be employed; Fig. 2 is a side view of a turbine disc provided with a supplemental ring as employed in the manufacture of my device; Fig. 3 is a perspective view of a blade adapted to be employed in the disc of Fig. 2; Fig. 4 is a view of the disc of Fig. 2 containing blades of the type shown in Fig. 3; Fig. 5 is a top view of the blading shown in Fig. 4 prior to the formation of a ring holding boss; Fig. 6 is a similar view after the provision of a boss and the application of suitable retaining rings; Fig. 7 is a sectional view of the turbine disc, together with a blade in side elevation; Fig. 8 is a side view of the completed structure; Fig. 9 is a view similar to Fig. 7 and embodying a modification in the ring mounting; Fig. 10 illustrates a modification of my invention wherein blades are retained in place by a pin rather than by an enlarged root; Fig. 11 illustrates one method of applying my invention to a disc carrying two rows of blading; and Fig. 12 illustrates another method of forming the same general structure as shown in Fig. 11.

In the manufacture of turbines, particularly of the disc type, it has been proposed to hold the blades in place either by transverse pins projecting through root portions thereof, or by employing expanded root portions engaging in undercut notches. While these structures are adequate so long as the

holding means remains in place, they at times fail because of slippage of the retaining means out of its appropriate position. 55

Accordingly, I mount blades in suitable blade-carrying elements in either one of the aforementioned ways, and I then shrink retaining rings on one or both sides of the blade-carrying means whereby such escape 60 of blade fastening structures is prevented. Preferably these retaining rings are shrunk in place upon bosses which taper slightly toward the disc so that, in shrinking, the rings are twisted or dished into firm engagement with the blades or blade roots to form a very tight fastening device. 65

Referring to the drawing for a more detailed understanding of my invention, I show a turbine of the single impulse wheel 70 type in Fig. 1 embodying a casing 15, a shaft 16, a disc 17 and a nozzle 18, any of which elements may be widely modified, without departing from the spirit and scope 75 of my invention.

In the manufacture of the disc 17, as shown in Fig. 2, it is provided with a temporary encircling ring 20 which is preferably shrunk in place. Holes 21 are then drilled, largely within the body of the disc 17, but 80 partially within the ring 20. The ring 20 is then removed, leaving a plurality of transverse peripheral notches in the disc 17, these notches being of circular cross section. Suitable blades for mounting in the disc 17 85 are provided as shown in Fig. 3, each blade 22 being provided with a transverse root portion 23 of substantially cylindrical cross section except that I preferably leave a flat portion on the under side thereof, as indicated at 24. 90

The blades 22-22 are slipped within the notches 21-21, as shown in Fig. 4, the flat portions 24 on the bottoms of the roots 23 causing the formation of segmental openings 95 at the bottoms of the notches 21-21. I then place suitable segmental-shaped wedges in each of these openings, as indicated more clearly at 25 in Fig. 7; the effect of the wedge being to cause firm engagement of the 100 respective root portions in their appropriate holding notches.

The resultant structure to this point is shown in plan view in Fig. 5, the blades

22—22 extending substantially to the outer surface of the disc 17 and the root portions 23—23 protruding through the sides of the disc, as indicated. I then machine away the 5 ends of the root portions 23, together with a portion of the disc 17, so as to form circumferential shoulders for the reception of retaining rings 26—26, as clearly shown in Fig. 7, the plan view of the structure thus 10 formed being shown in Fig. 6, and the side view of the finished rotor being shown in Fig. 8.

The rings 26 are shrunk firmly in place and effectually prevent the escape of the root 15 portions 23 and of the wedges 25 from their appropriate position within the blade-carrying notches.

Obviously the blade roots 23 and the wedges 25 may be made shorter than I have 20 described in connection with Figs. 4 and 5, and the disc 17 may be formed initially with a pair of circumferential shoulders so as to obviate the necessity of machining out the 25 grooves for the rings 26—26 after assembly, but I find that a much neater and more effective structure may be provided by following the procedure which I have first above outlined.

Referring to Fig. 9, I show in exaggerated 30 form a feature of my invention which I consider highly advantageous. The shoulders or bosses formed on the disc 17 for the reception of the retaining rings 26—26 may run normal to the plane of the disc, but these 35 holding bosses preferably taper slightly toward the disc, whereby when the rings 26—26 are shrunk in place, the shrinking upon said tapered bosses causes the rings to slightly twist or dish, whereby they are 40 forced into firm engagement, both with the roots of the blades and with the blade holding means, as indicated. Furthermore, the rings are more effectually held in place than would be the case if they were shrunk upon 45 a cylindrical boss.

In the form of my invention shown in Fig. 10, the disc 17 is provided with a pair of peripheral flanges 30 and 31 between which a 50 suitably formed root portion 32 is disposed, being held in place as by suitable transverse holding pins 33. Suitable retaining rings 26—26 are then mounted in place to prevent the escape of the pins 33 and also to give a smooth and pleasing appearance to the entire 55 structure.

In the form of my invention shown in Fig. 11, a disc 17' carries a rim 40 having two blade-carrying flanges 41 and 42, thereupon, 60 each of which carries suitable blading as indicated, this blading being shown as held in place in the same manner as indicated in Fig. 7. This structure has the marked disadvantage that the inner rings 26—26 cannot be formed integrally and slipped into place, 65 but they must be split in one or more places,

placed between the flanges 41 and 42 and then welded or otherwise joined into continuous rings, all prior to the shrinkage operation. Inasmuch as this is a troublesome and unsatisfactory operation, I prefer to employ the 70 structure shown in Fig. 12 for a disc carrying two rows of blading. The disc 17'' has a rim 40' with blade holding notches drilled in from opposite sides thereof for the reception of blade holding roots, all of the general 75 type shown in Fig. 4. Suitable rings 26—26 are then disposed in place to prevent the escape of the blades, movement of the blade holding structures toward the center of the disc 17'' being prevented by the solid abutments indicated at 45—45.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended 90 claims.

What I claim is:

1. In an elastic fluid turbine, the combination with a blade-carrying disc, of blades carried thereby and mounted by holding means extending transversely of said disc, and holding rings to prevent movement of said holding means transversely of said disc, said holding rings being shrunk in place.

2. In an elastic fluid turbine, the combination with a blade-carrying disc, of an inwardly tapering boss formed around the disc near its periphery, blades carried by the disc and mounted by holding means extending transversely of said disc, and a holding ring to prevent movement of said holding means transversely of said disc, said holding ring being slipped over the boss and shrunk in place thereon, whereby said ring is twisted into firm engagement with 100 said holding means.

3. In an elastic fluid turbine, the combination with a disc provided with a plurality of transverse undercut notches in the periphery thereof, of blades provided with root portions adapted to fit within said notches, respectively, bosses formed on the sides of the disc near the periphery thereof and retaining rings mounted upon the sides of 115 said disc and shrunk upon the bosses to restrain said root portions in place.

4. In an elastic fluid turbine, the combination with a disc provided with a plurality of transverse undercut notches in the periphery thereof, of blades provided with root portions adapted to fit within said 125 notches, respectively, bosses formed on the sides of the disc adjacent the notches and tapering slightly inward of the disc, and retaining rings mounted upon the sides of 130

said disc and shrunk upon the bosses to restrain said root portions in place, whereby said rings in shrinking are twisted into firm engagement with said blades.

5 5. In an elastic fluid turbine, the combination with a disc provided with a plurality of transverse undercut notches in the periphery thereof, of blades provided with root portions adapted to fit within said notches and to substantially fill the same except for an opening at the bottom of each notch, a tightening wedge in each of said openings, respectively, and retaining rings mounted upon the sides of said disc to restrain said root portions and said wedges in place.

10 6. In an elastic fluid turbine, the combination with a disc provided with a plurality of transverse undercut notches in the periphery thereof, of blades provided with root portions adapted to fit within said notches and to substantially fill the same except for an opening at the bottom of each notch, a tightening wedge in each of said openings, respectively, bosses formed on the sides of the disc adjacent the notches, and retaining rings mounted upon the sides of said disc to restrain said root portions and said wedges in place.

15 7. In an elastic fluid turbine, the combination with a disc provided with a plurality of transverse undercut notches in the periphery thereof, of bosses formed on the sides of the disc adjacent the notches and tapering slightly toward the disc, blades provided with root portions adapted to fit within said notches and to substantially fill the same except for an opening at the bottom of each notch, a tightening wedge in each of said openings, respectively, and retaining rings mounted upon the sides of said disc and shrunk upon the bosses to restrain said root portions and said wedges in place, whereby said rings in shrinking are twisted into firm engagement with said blades.

20 8. In an elastic fluid turbine, the combination with a disc provided with a transverse undercut notch in the periphery thereof, said notch being of circular cross-section, of a blade having a root portion shaped to fit within said notch except for a segmental opening at the bottom thereof, a segmental wedge disposed within said opening and adapted to tightly fill the same and a retaining ring on one side of said disc and overlying said root portion and said wedge, whereby said elements are restrained from movement out of said notch in the direction of said ring.

25 9. In an elastic fluid turbine, the combination with a disc provided with a transverse undercut notch in the periphery thereof, said notch being of circular cross-section, of a blade having a root portion shaped to fit within said notch except for a segmental

opening at the bottom thereof, a segmental wedge disposed within said opening and adapted to tightly fill the same and a retaining ring on one side of said disc and overlying said root portion and said wedge, whereby said elements are restrained from movement out of said notch in the direction of said ring, said ring being shrunk in place upon a suitable boss provided on the side of said disc. 75

10 10. In an elastic fluid turbine, the combination with a disc provided with a transverse undercut notch in the periphery thereof, said notch being of circular cross-section, of a boss formed on the side of the disc adjacent the notch and tapering slightly toward the disc, a blade having a root portion shaped to fit within said notch except for a segmental opening at the bottom thereof, a segmental wedge disposed within said opening and adapted to tightly fill the same and a retaining ring shrunk on the boss and overlying said root portion and said wedge, whereby said elements are restrained from movement out of said notch in the direction of said ring, and said ring in shrinking is twisted into firm engagement with said blade. 80 85 90

11 11. In an elastic fluid turbine, the combination with a disc provided with a plurality of transverse undercut notches in the periphery thereof, of blades provided with root portions adapted to fit within said notches, respectively, and a retaining ring mounted upon one side of said disc and overlying said root portion, whereby said root portions are restrained from movement out of said notches in the direction of said ring. 95 100

12 12. In an elastic fluid turbine, the combination with a disc provided with a plurality of transverse undercut notches in the periphery thereof, of a boss formed on one side of the disc adjacent the notches and tapering slightly toward the disc, blades provided with root portions adapted to fit within said notches, respectively, and a retaining ring shrunk on the boss and overlying said root portion, whereby said root portions are restrained from movement out of said notches in the direction of said ring, and said ring in shrinking is twisted into firm engagement with said blades. 110 115

13 13. In an elastic fluid turbine, the combination with a blade-carrying disc, of blades carried thereby and mounted by holding means extending transversely of said disc, and a holding ring shrunk upon a boss upon one side of said disc, said ring overlying said holding means, whereby they are restrained from movement out of said disc in the direction of said ring. 120 125

14. In an elastic fluid turbine, the combination with a blade-carrying disc, of blades carried thereby and mounted by hold- 130

ing means extending transversely of said disc, a boss formed on one side of the disc, and a holding ring shrunk upon the boss, said ring overlying said holding means, whereby they are restrained from movement out of said disc in the direction of said ring, and said boss tapering slightly toward said

disc, whereby said ring in shrinking is twisted into firm engagement with said blades.

In testimony whereof, I have hereunto subscribed my name this 17th day of March, 1924.

ALEXANDER T. KASLEY.
